United States Patent Office

Des. 224,162
Patented July 4, 1972

224,162

MOTION PICTURE CAMERA HOUSING

Walter H. Bach, 1771 N. Crescent Heights Blvd.,
Los Angeles, Calif. 90069

Filed Sept. 22, 1970, Ser. No. 25,135

Term of patent 14 years

Int. Cl. D16—01

U.S. Cl. D61—1

Fig. 1

Fig. 3

Fig. 2

Fig. 4

Fig. 5

FIG. 1 is a perspective view of a motion picture camera housing showing my new design;

FIG. 2 is a right side elevational view of the motion picture camera housing shown in FIG. 1;

FIG. 3 is a front elevational view thereof;

FIG. 4 is a rear elevational view thereof; and

FIG. 5 is a bottom plan view thereof.

I claim:

The ornamental design for a motion picture camera housing, as shown.
